US0D1112313S

(12) United States Design Patent (10) Patent No.: US D1,112,313 S
(45) Date of Patent: * Feb. 10, 2026

(54) TYPE FONT

- (71) Applicant: Apple Inc., Cupertino, CA (US)
- (72) Inventors: Andrew Patrick Clymer, San Jose, CA (US); Hanwen Fan, San Jose, CA (US); Bobby Cole Martin, Jr., Palo Alto, CA (US); Michael Tettey Nartey, San Jose, CA (US); Vincenzo Vuono, Cupertino, CA (US)
- (73) Assignee: Apple Inc., Cupertino, CA (US)
- () Term: 15 Years
- (21) Appl. No.: 29/978,378
- (22) Filed: Dec. 12, 2024

Related U.S. Application Data

- (63) Continuation of application No. 29/882,670, filed on Jan. 17, 2023, now Pat. No. Des. 1,060,389.
- (51) LOC (15) Cl. 18-03
- (52) U.S. Cl. D18/24; D18/26
- (58) Field of Classification Search
USPC D18/24-26, 28, 30; D14/490
CPC .. B41B 1/02; B41B 1/025; G09B 1/04; G09B 3/04
